ADHESIVE APPLICATOR FOR A CAN LABELING MACHINE

Ralph J. Mattingly, deceased, late of Rising Sun, Ind., by
Richard R. Mattingly, P.O. Box 325, Aurora, Ind., exec-
utor, and John J. Mattingly, 213 Front St., Rising Sun,
Ind.

Original application Jan. 20, 1955, Ser. No. 483,074, now
Patent No. 2,868,403, dated Jan. 13, 1959. Divided
and this application Dec. 24, 1958, Ser. No. 782,833
11 Claims. (Cl. 156—357)

The present invention appertains in general to labeling machines and more particularly to an apparatus for applying an adhesive to labels in a labeling machine.

This application is a division of U.S. application Serial No. 483,074, filed January 20, 1955, and issued January 13, 1959, as Patent No. 2,868,403, for Can Labeler.

An object of the present invention is to provide an improved adhesive applicator for a can labeling machine.

Another object is to provide a glue bar that reduces the tendency for labels to stick to parts of a labeling machine.

Another object is to provide an adhesive applicator that supplies a uniform quantity of adhesive material to successive labels in a stack.

Another object of the present invention is to provide an adhesive applicator that operates when successive cans advancing through a labeling machine are spaced in a predetermined relationship.

Another object is to provide an adhesive applicator that operates in response to the flow of cans through a can labeling machine and applies adhesive to the lap end of a label.

Another object is to provide an adhesive applicator for a can labeling machine that is automatically raised from a position of contact with a stack of labels to an inoperative position when the flow of cans through the labeling machine is interrupted.

Another object is to provide means for controlling the flow of glue to a glue bar of a can labeling machine so that the flow of glue to the bar is cut off when the movement of cans through the machine is interrupted.

Another object of our invention is the provision of improved means for applying a longitudinal glue seam to each label as it is withdrawn from the stack of labels, such means including means effective automatically, upon stoppage of movement of cans through the machine for any purpose, to prevent sticking of the labels to the glue applying means.

Other objects and advantages of the present invention will become apparent from the following description and drawings, in which:

FIG. 1 is a side elevation with parts in section of a can labeling machine embodying the adhesive applicator of the present invention.

FIG. 2 is a plan view of the labeling machine illustrated in FIG. 1.

FIG. 3 is a side elevation with parts in section of a valve mechanism for the glue applicator of the present invention.

FIG. 4 is an enlarged fragmentary plan with parts in dotted line illustrating an end portion of the glue applicator.

FIG. 5 is a section taken along the line 5—5 of FIG. 4.

FIG. 6 is a section taken along the line 6—6 of FIG. 4.

In FIGS. 1 and 2 of the drawings spaced apart tracks 1 and 2 are illustrated. These tracks are provided with side guides 3 along which end edges or beads of can 4 are adapted to travel, the cans being fed onto the tracks 1 and 2 in any suitable manner. In a canning factory, for example, the cans may be fed directly from the can sealing means.

2

Mounted on the machine frame 5 is a pair of arms 6 and 7 (FIG. 2), the arms being pivoted to the frame adjacent their rear ends by means of pins 8 and 9. The arms 6 and 7 are joined together intermediate their ends by a cross bar 10, and the arms are urged downwardly in a counterclockwise direction (FIG. 1) by means of springs 11 and 12 (FIG. 2) each of which is compressed between one of the arms 6 or 7 and a bracket member 13 or 14. Suitable studs, such as the studs 15 and 16 (FIG. 1), are provided to maintain the springs in proper position between the arms and the bracket members. The bracket members 13 and 14 also carry depending fingers 17 and 17a, respectively, the lower ends of which are inturned and adapted to engage beneath the cross bar 10. The fingers are threaded at their upper ends and are axially adjustable by means of nuts 18 and 19 (FIG. 1), the fingers thus serving as stops limiting the counterclockwise movement of the arms 6 and 7.

At their outer ends the arms 6 and 7 carry rocker arms 20 and 21 (FIG. 2) which are mounted to rock relative to the arms 6 and 7. Rotatable shafts 22 and 23 extend between the ends of the arms and pairs of rollers 24 and 25 are mounted on the shafts 22 and 23, respectively. The pairs of rollers are fixed to the shafts and are adapted to be rotated thereby, the shaft 22 being driven by a chain 27 which passes around a sprocket 26 keyed to shaft 22 and around a sprocket 28 operatively connected to the drive mechanism for the machine. A chain 29 passing around sprockets 30 and 31 serves to drive the shaft 23 from shaft 22. The rocker arms 20 and 21 are provided with angular extensions 32 and 33 between which a shaft 34 extends. This shaft mounts a collar 35 to which one end of a shaft 36 is connected, the opposite end of the shaft extending freely beyond a bracket 37 through which the shaft passes. Springs 38 and 38a surround the shaft, one on each side of the bracket 37, and the springs 38 and 38a are compressed between the bracket 37 and collars 39 and 39a, respectively, thereby balancing the rocker arms and rollers in an intermediate position.

The can spacing or metering means will normally assume a position in which the rocker arms 20 and 21 and rollers 24 and 25 lie substantially parallel to the tracks 1 and 2, and in the path of the advancing cans, as seen in FIG. 1. As the can 4a rolls down the tracks, it will first contact the rollers 24 and the momentum of the can will be sufficient to move these rollers upwardly, thereby causing the rocker arms 20 and 21 to rock in a clockwise direction against the compression of the spring 38. The upward movement of the rollers 24 permits the can 4a to pass therebeneath, whereupon it contacts the lowered rollers 25 which momentarily arrest its forward movement. The can will, however, rock the rollers 25 upwardly, this time against the compression of the spring 38a, and the can will then pass beneath the rollers 25 and on down the tracks. At the same time the rollers 24 are rocked downwardly into the path of the next adjacent can 4b, thereby momentarily arresting the forward movement of the can 4b. Once the can 4a has passed beyond the rollers 25, these rollers will be free to move downwardly under the influence of the can 4b urging the rollers 24 upwardly, whereupon the cycle is repeated. In this way, the cans are evenly metered in their forward movement through the machine.

After the cans pass the spacing or metering means, they are contacted by moving belt 40 and 41 (FIG. 2) which move the cans forwardly along the tracks 1 and 2. Suitable hold down means in the form of rollers 42 (FIG. 1) are provided to maintain the lower flights of the belts in contact with the cans, the rollers being mounted on arms, such as the arm 43, and urged into engagement with the belts by means of springs, such as

the spring 44. As the cans move along they pass over a glue pot 45 (FIG. 1) in which is positioned a glue applicator comprising a plurality of glue wheels 46 mounted on a rotatable shaft 47 driven by means of a chain 48 operatively connected to the machine drive. The glue wheels 46 are positioned in spaced apart relation and are adapted to apply a plurality of spaced apart spots of glue to the cans.

Since the cans are not ordinarily truly cylindrical and may have irregularities in their surfaces, the individual glue wheels are resiliently mounted so that they will contact the periphery of the cans irrespective of irregularities therein, the wheels individually compensating for any irregularities encountered in the surfaces of the cans. The glue wheels 46 and the operation thereof, are described in detail in our aforementioned copending application.

Subsequent to the application of the glue spots to the advancing cans, the cans pass over a stack of labels 60 extending upwardly between the tracks 1 and 2 and supported on a liftable platform 61 (FIG. 1). The stack 60 is so arranged that the uppermost label in the stack will lie in a position to be contacted by a can passing over it and the glue spots on the can will engage the label and cause the label to adhere to the can. Continued forward movement of the can serves to wrap the label about the cylindrical surface of the can.

In order to assure proper contact between the cans and the stack of labels, we provide automatically acting means to raise the stack as the labels are removed. To this end, an opening is provided in the track 1 adjacent the leading edge of the stack and a depressible bar 62 (FIG. 1) is fitted in this opening. When the stack is in contact position the end edge of the can will not contact the bar 62, since the stack will lift the can just slightly above the track 1. However, as the stack is depleted, its level will reach a point such that the cans will contact the bar 62 and cause it to be depressed. Depression of the bar 62 causes a rod 63 secured thereto to move downwardly into contact with a button 64 of an actuating switch 65. This switch will serve to actuate mechanism (not shown) serving to lift a rack or plunger 66 which controls the movement of the liftable platform 61, thereby moving the platform upwardly a distance sufficient to raise the upper surface of the stack above the level of the tracks 1 and 2 and into can contacting position. Suitable spring means, indicated at 67 and 68, are provided to normally bias the depressible bar 62 and the rod 63 to uppermost position in which the upper surface of the bar coincides with the upper surface of the rail 1.

With this arrangement, the stack of labels is automatically maintained at the proper height and the mechanism is immediately responsive to a reduction in the height of the stack sufficient to permit the cans to contact the depressible bar.

Intermediate the leading and trailing ends of the stack of labels, the tracks 1 and 2 are inclined upwardly so as to raise the cans above the rear portion of the stack so as to pass over a glue bar 70 (FIGS. 1 and 2) which rests on the rear edge of the stack and acts to apply a transverse band of adhesive to the trailing edge of each label. As best seen in FIG. 6, the glue bar is hollow and has a flattened undersurface 71 for contact with the labels, the undersurface having a plurality of perforations 72 extending along its length to deposit adhesive 73 on the labels. The adhesive is continuously circulated through the glue bar, being pumped through a tube 74 (FIG. 1) from a reservoir 75 by a pump 76 and returned to the reservoir through a tube 77 (FIGS. 1 and 2). The band of adhesive formed by the glue bar or tube 70 serves to connect the leading and trailing edges of the labels, the labels being of a length such that upon being wrapped around the cans their leading and trailing edges will overlap sufficiently to form a glue seam. In addition to applying glue to the trailing edge of the labels, the glue

bar acts to hold each label in taut condition as it is being wrapped about the can. The label will be pulled from beneath the glue bar as the forward movement of the can continues, thereby permitting the glue bar to contact and apply adhesive to the next adjacent label.

There are times, during the operation of the machine, when the cans are not fed through the machine at regular intervals and when this occurs there is a tendency for the uppermost label to stick to the glue bar with a result that it will be either torn apart or else stick in the machine. Even if the label tears free, the residue adhering to the glue bar acts to foul the glue bar and subsequent labels do not receive the proper amount of adhesive. To remedy this situation, we have provided means which act to automatically raise the glue bar from contact with the stack of labels should the flow of cans through the machine be interrupted for any reason.

A pair of arms 78 and 79 (FIG. 2) is rotatively connected to a cross bar 80 journaled on the machine frame, and at their ends the arms are provided with outwardly extending pins 81 (FIGS. 4 and 5) having heads 82. Slidably supported on these pins are depending ears 83 of collars 84 which surround the ends of the glue bar 70. Springs 85 are interposed between the ends of the arms and the depending ears, thereby resiliently mounting the glue bar relative to the arms. Curved fingers 86 and 87 (FIG. 2) are fixed to the cross bar 80 for contact with the under-surfaces of the arms 78 and 79; and a bar 89 also extends between the arms and has a spring 90 (FIG. 1) secured thereto for urging the arms and the glue bar carried thereby downwardly into contact with the stack of labels.

A rocker arm 91 (FIG. 1) is connected to an end of the cross bar 80, the arrangement being such that movement of the rocker arm in one direction will rotate the cross bar so as to bring the curved fingers 86 and 87 into contact with the arms 78 and 79, thereby causing them to lift the glue bar upwardly away from the stack of labels against the tension of the spring 90.

Movement of the rocker arm 91 is controlled by a plunger 92 which passes through a control cylinder 93 and is connected at its free end to the piston rod 94 of air cylinder 95 having a piston 96. The rocker arm 91 is normally urged away from the glue bar lifting position by a spring 97. During the normal operation of the machine, the glue bar is maintained in contact with the stack of labels by the spring 90, and the spring 97 serves to hold the arm 91 in an inoperative position. However, should the normal flow of cans be interrupted, then compressed air will be introduced into the air cylinder 95 through a conduit 99 thereby moving the piston rod 94 and plunger 92 against the tension of the spring 97. This will cause the rocker arm 91 to move in a clockwise direction (FIG. 1), thereby raising the curved fingers 86 and 87 and causing the glue bar to be lifted from the stack of labels.

The supply of compressed air fed to the air cylinder through the conduit 99 is controlled by a valve means 100 (FIGS. 1 and 3) which, in turn, is responsive to the passage of the cans through the machine.

Referring now to FIGURE 3 of the drawings, the valve means 100 comprises a body 101 having an air chamber 102 including valve seats 103 and 104 adapted to receive the valves 105 and 106, respectively. A passageway 107 opens into the valve seat 103 through which compressed air enters the air chamber, being supplied from a source of air under pressure (not shown) and entering the passageway through conduit 108. Similarly, the valve seat 104 is provided with a vent passageway 109.

The valves 105 and 106 are adapted to be opened by means of stems 110 and 111, respectively, which are alternately contacted by the pivot plate 112. When the pivot plate contacts the stem 111, the valve 106 will be opened, thereby venting the air chamber 102 through

the vent passageway 109. Conversely, when the pivot plate is rocked to actuate stem 110, the valve 106 will be closed by spring 113 and the valve 105 will be opened against the tension of spring 114, thereby connecting the air chamber to the intake passageway 107.

Movement of the pivot plate 112 is controlled by an arm 114' which is engaged between opposed springs 115 and 116 (FIG. 1) surrounding a rod 117, the springs being engaged between stops 118 and 119. A spring 120 urges the rod 117 to the uppermost position, in which position the valve 105 is open to thereby supply air under pressure to the air chamber.

The rod 117 is, however, normally held in its lowermost position against the compression of spring 120 by means of the arm 121 connected at one end to the rod 117 and carrying on its opposite end a roller 122, the arm being pivoted intermediate its ends to a brace 123. The roller 122 is adapted to contact the traveling belt 40, and the arrangement is such that the cans, as they move through the machine, maintain the lower flight of the belt 40 in sufficiently taut condition to support the roller 122 and the adjacent end of the arm 121 in a raised position, thereby lowering the opposite end of the arm and the rod 117.

Referring now to the control cylinder 93 (FIG. 1), it will be noted that the glue bar feed tube 74 is connected to one end of the cylinder in such fashion that the piston 124 will effectively close the tube when moved to the right-most end of the cylinder. Thus, at such times as the plunger 92 acts to move the rocker arm 91 to lift the glue bar from the stack of labels, the control cylinder will shut off the flow of adhesive to the glue bar.

In the operation of the glue bar mechanism, the cans as they move along the tracks in the normal operation of the machine will maintain the roller 122 in its elevated position, thereby holding the rod 117 in its lowermost position and maintaining the valve means 100 in the vent position. The rocker arm 91 is thus urged in a counterclockwise direction by the spring 97, thereby maintaining the fingers 86 and 87 out of contact with the arms 78 and 79 of the glue bar, the glue bar being held in contact with the stack of labels by means of the spring 90. However, should the normal feeding cycle of the cans be interrupted and a gap occur between adjacent cans, the belt 40 will sag sufficiently to permit the roller 122 to move downwardly, being urged by the spring 120 which also acts to urge the rod 117 upwardly, thereby moving the plate 112 to its alternate position. This movement opens the valve 105 and causes air under pressure to flow through the air chamber 102 and into the cylinder 95 so as to drive the piston 96 to the right, as seen in FIG. 1, thereby moving the rocker arm in a clockwise direction against the tension of spring 97. Movement of the rocker arm in turn raises the fingers 86 and 87, thereby lifting the arms 78 and 79 which raise the glue bar away from the stack of labels. Air pressure will be applied so long as the flow of cans is interrupted, but once the normal flow is resumed, the belt 40 will be tightened, the roller 122 lifted and the rod 117 moved downwardly, thereby closing valve 105 and opening valve 106, the opening of the latter valve acting to vent the cylinder 95 through the conduit 99, air chamber 102 and vent 109. This action releases the rocker arm 91 for return movement under the influence of spring 97, thereby releasing the glue bar for downward movement under the influence of spring 90.

It will be understood that modifications and variations of the embodiments of the invention disclosed herein may be resorted to without departing from the spirit of the invention and the scope of the appended claims.

Having thus described our invention, what we claim as new and desire to protect by Letters Patent is:

1. In a labeling machine wherein cans are advanced along a path in a predetermined spaced apart relation

and wherein a label is disposed in the path of an advancing can, and including means for advancing the cans along said path, the improvement which comprises an applicator for contacting the label to apply an adhesive along an edge of the label, means supporting said applicator for movement between a label contacting position and a position removed from contact with a label, and fluid responsive means operatively connected to said can advancing means and actuated when the spacing between successive cans exceeds a predetermined amount for actuating said applicator support means to move said applicator from said label contacting position to the position removed from contact with a label.

2. In a labeling machine wherein cans are advanced along a path in a predetermined spaced apart relation and wherein a label is disposed in the path of an advancing can, the improvement which comprises means for advancing the cans along said path, a hollow bar having perforations therein for contacting the label to apply adhesive along an edge of the label, means supporting said hollow bar for movement between a label contacting position and a position removed from contact with a label, means for circulating liquid adhesive through said hollow bar, fluid responsive means connected to be actuated by said can advancing means and actuated when the spacing between successive cans exceeds a predetermined amount for actuating said hollow bar support means to move said hollow bar from said label contacting position to the position removed from contact with a label, and means effective when said hollow bar is removed from the label contacting position for cutting off the flow of adhesive through said hollow bar.

3. In a labeling machine wherein cans are advanced along a predetermined path and wherein a label is disposed in the path of an advancing can, a belt for advancing the cans along said path, said belt being tensioned by the normal flow of advancing cans through said machine and being slackened when the normal flow of cans through said machine is interrupted, a hollow bar having perforations therein disposed adjacent said path for contacting the label to apply an adhesive along an edge of the label, means supporting said hollow bar for movement between a label contacting position and a position removed from contact with a label, means for circulating liquid adhesive through said hollow bar, fluid actuated means for actuating said hollow bar support means to move said hollow bar from said label contacting position to the position removed from contact with a label and for cutting off the flow of liquid adhesive to said hollow bar when said bar is in a position removed from contact with a label, and valve means responsive to said belt being slackened for operating said fluid actuated means.

4. In a labeling machine wherein cans are advanced along a predetermined path and wherein a label is disposed in the path of an advancing can, a belt for advancing the cans along said path, said belt being tensioned by the normal flow of advancing cans through said machine and being slackened when the normal flow of cans through said machine is interrupted, a hollow bar having perforations therein disposed adjacent said path for contacting the label to apply an adhesive along an edge of a label, means supporting said hollow bar for movement between a label contacting position and a position removed from contact with a label, means for circulating liquid adhesive through said hollow bar, aligned cylinders including pistons connected for simultaneous movement, means for connecting the piston of one of said cylinders to said hollow bar support means for moving said hollow bar from said label contacting position to the position removed from contact with the label and for cutting off the flow of liquid adhesive to said hollow bar when said bar is in a position removed from contact with a label, means communicating with a second of said cylinders

inders for establishing a flow of fluid thereinto, and valve means responsive to said belt being slackened and arranged to control the flow of fluid into said second cylinder for actuating said pistons.

5. In a labeling machine wherein cans are advanced along a predetermined path and wherein a label is disposed in the path of an advancing can, a belt for advancing the cans along said path, said belt being tensioned by the normal flow of advancing cans through said machine and being slackened when the normal flow of cans through said machine is interrupted, a hollow bar having perforations therein disposed adjacent said path for contacting the label to apply an adhesive along an edge of a label, means supporting said hollow bar for movement between a label contacting position and a position removed from contact with a label, means for circulating liquid adhesive through said hollow bar, fluid actuated means for actuating said hollow bar support means to move said hollow bar from said label contacting position to the position removed from contact with a label and for cutting off the flow of liquid adhesive to said hollow bar when said bar is in a position removed from contact with a label, means communicating with said fluid actuating means for establishing a flow of fluid thereinto, valve means operative for controlling the flow of fluid into said fluid actuated means, a spring loaded rod disposed adjacent said belt and actuated in response to said belt being slackened, and a pivot plate disposed adjacent said rod and actuated by said rod for controlling the operation of said valve whereby said fluid actuating means is operated when said belt is slackened.

6. In a labeling machine wherein cans are advanced along a predetermined path and wherein a label is disposed in the path of an advancing can, a belt for advancing the cans along said path, said belt being tensioned by the normal flow of advancing cans through said machine and being slackened when the normal flow of cans through said machine is interrupted, an adhesive applicator disposed adjacent said path for contacting the label to apply an adhesive along an edge of the label, support arms connected at the free end thereof to said adhesive applicator, a cross bar mounted for rotation and connected to the proximal ends of said support arms to enable said support arms to pivot thereabout, lifting fingers fixed to said cross bar and arranged to contact the lower surfaces of said support arms, means connected to said support arms for urging said support arms to move in a direction for positioning said adhesive applicator in contact with a label, a rocker arm connected to said cross bar for rotating said cross bar to move said fingers into contact with said support arms to lift said adhesive applicator in a direction for removing it from contact with a label, and fluid actuated means responsive to a change in the tautness of said belt for controlling the operation of said rocker arm.

7. In a labeling machine having means for moving cans therethrough on spaced tracks and including a stack of labels positioned in can contacting position, the combination of an adhesive applying tube having adhesive continuously circulating therethrough and positioned to apply adhesive to an edge of the uppermost label in the stack and movable to a position spaced from the labels, means connected to said adhesive applying tube and responsive to the movement of cans through the machine for moving said tube to the position spaced from the labels, and means effective upon the movement of said tube to stop the circulation of adhesive therethrough.

8. In a labeling machine wherein cans are moved through the machine on a spaced apart pair of tracks, and wherein a stack of labels is adapted to be supported between the tracks in can contacting position, the combination of a hollow glue bar having perforations therein for applying adhesive to the trailing edge of the upper-

most label in the stack, said glue bar being movable from an operative to an inoperative position, means for continuously circulating liquid adhesive through said hollow glue bar, an air cylinder having a piston operatively connected to the said glue bar, and air valve means responsive to the movement of cans through the machine for alternatively pressurizing and venting said air cylinder for moving glue bar from one position to the other.

9. In a labeling machine wherein cans are moved through the machine on a spaced apart pair of tracks, and wherein a stack of labels is adapted to be supported between the tracks in can contacting position, the improvement which comprises a hollow glue bar having perforations therein for applying adhesive to the trailing edge of the uppermost label in the stack, means for moving said glue bar from an operative to an inoperative position said means including an air cylinder having a piston operatively connected to said glue bar and including valve means for alternatively pressurizing and venting said cylinder, means for continuously circulating adhesive through said hollow glue bar, a control cylinder having a piston therein effective in one position, to cut off the flow of adhesive to said glue bar, and means interconnecting the piston of said air cylinder with the piston of said control cylinder for joint movement, whereby the pressurizing of said air cylinder will raise the glue bar to its inoperative position and cause the piston in said control cylinder to shut off the flow of adhesive through said glue bar.

10. In a labeling machine wherein cans are moved through the machine on a spaced apart pair of tracks, and wherein a stack of labels is adapted to be supported between the tracks in can contacting position, the improvement which comprises a hollow glue bar having perforations therein for applying adhesive to the trailing edge of the uppermost label in the stack, said glue bar being movable from an operative to an inoperative position, means for continuously circulating liquid adhesive through said hollow glue bar, an air cylinder having a piston operatively connected to said glue bar, an air valve responsive to the movement of cans through the machine for alternatively pressurizing and venting said air cylinder for moving the glue bar from one position to the other, and means effective upon movement of the glue bar to the inoperative position for cutting off the flow of adhesive through said hollow glue bar.

11. In a machine for labeling cylindrical containers being advanced along a predetermined path toward a label disposed for engagement by the leading container, the combination of means for advancing the containers along said path, an applicator disposed adjacent said path in normal contact with said label to apply an adhesive along an edge thereof, means for moving said applicator between its said normal label contacting position and a position out of contact with the label, and movable means engaging said container advancing means and responsive to the absence of a container engaging an adjacent portion of the advancing means for actuating said applicator moving means to shift said applicator from said label contacting position to said position out of contact with the label.
